UNITED STATES PATENT OFFICE.

EDWARD B. HYDE, OF BLOOMFIELD, NEBRASKA.

CULTIVATOR.

1,262,800.

Specification of Letters Patent. Patented Apr. 16, 1918.

Application filed November 2, 1915. Serial No. 59,221.

To all whom it may concern:

Be it known that I, EDWARD B. HYDE, a citizen of the United States, residing at Bloomfield, in the county of Knox and State 5 of Nebraska, have invented certain new and useful Improvements in Cultivators, of which the following is a specification.

My invention relates to new and useful improvements in cultivators, and more particularly to a cultivator of the wheeled type.

The primary object of the invention is the provision of a cultivator of this character which is balanced from the driver's seat.

A further object of the invention is the provision of connecting means between the balancing seat and gang beams whereby the shovels will remain the same depth in the ground at all times.

A still further object of the invention is the provision of means for adjusting the several parts whereby the balance may be used by drivers or operators of different weights.

With these and other objects in view the invention consists in the novel details of construction and arrangement of parts which will be more clearly understood from the following description and drawings, in which,

Figure 1 is a view in side elevation.

Fig. 2 is a front view partly in section, and

Fig. 3 is a detail of a leaf spring.

In the drawings, the numeral 1 indicates the tongue or pole of ordinary construction 35 to which is secured the arch member 2 to which are hingedly connected the gang beams 3 of ordinary construction. A brace 4 extends from the tongue or pole 1 to the arch member for bracing the same. The 40 axle 5 is connected to one end of the tongue and receives the wheels 6. Suitable adjusting means shown generally in the drawings may be used for adjusting the axle but form no part of the present invention and will 45 not be described in detail. The horses are connected to the swingletree 7 and so far as the parts above described are concerned they are of the construction now commonly in use.

My invention consists more particularly 50 in means for balancing the pole and gangs. The seat beam 8 is pivotally secured to the

axle 5 by means of a clip 9, to which is connected the rear end of pole 1 and at the opposite end is located the seat 10 to be occupied by the driver. On the forward end 55 of the seat beam is secured a leaf spring 11 having a depending eye 12 on each end thereof. A plurality of eye members 13 are provided on the gang beams and coil springs 14 are adapted to be connected to each of 60 the depending eye members 12 on the leaf spring and to the eye members 13 on the gang beams. The coil springs 14 may be adjusted by placing them in the various eyes 13.

It will be seen that I have provided a cultivator by means of which the pole and gangs are balanced or regulated by the weight of the driver. For a driver of greater or less weight the ends of the coil 70 springs 14 are adjusted in the eyes 13 on the gang beams. By the construction above described the shovels connected to the gang beams are always held in the ground at the same depth. In going over uneven ground 75 the springs 14 take up the jar and give the plow shovels an even and elastic motion instead of the jam and jerk of the cultivators now in common use. At the same time it lessens the draft and adds to the convenience 80 of the operator.

While I am aware that it is not broadly new to have a seat balance cultivator I believe that it is new and claim the springs connecting the ends of the seat beam and the 85 gang beams. Not only is resilient action secured from the coil springs 14 but also from the leaf spring 11.

Having fully described the invention what I claim as new and desire to secure by Letters Patent is:—

1. In a cultivator having a U-shaped axle, the combination with plow beams, a seat beam pivotally mounted on said U-shaped axle, a resilient member secured to one end 95 of said seat beam and coiled springs adapted to unite the resilient member and the plow beam.

2. In a cultivator having a U-shaped axle, the combination with a plurality of plow beams, of longitudinally spaced eyes located thereon, a seat beam pivotally supported on

said U-shaped axle, a leaf spring mounted on said seat beam, depending eyes at each end thereof, and coiled springs adjustably connecting the leaf spring and plow beams, 5 said coil springs having a hook on each end thereof adapted to engage the depending eyes on the plow beams respectively.

In testimony whereof I affix my signature in presence of two witnesses.

EDWARD B. HYDE.
